[57] CLAIM

The ornamental design for an electronic game machine
with integral timer, substantially as shown and de-
scribed.

DESCRIPTION

FIG. 1 is a perspective view of the electronic game
machine with integral timer showing my new design, all
sides of the machine being identical;

FIG. 2 is bottom plan view thereof on a reduced scale;

FIG. 3 is a perspective view thereof with the keyboards
in the game playing position, all sides of the machine
being identical.
